UNITED STATES PATENT OFFICE.

REINHOLD BECKER, OF KREFELD, GERMANY.

AUTOMATIC FIREARM.

1,144,285.

Specification of Letters Patent. Patented June 22, 1915.

Application filed October 27, 1914. Serial No. 868,898.

To all whom it may concern:

Be it known that I, REINHOLD BECKER, a subject of the German Emperor, residing at 45 Deutscher Ring, Krefeld, Germany, have invented certain new and useful Improvements in Automatic Firearms, of which the following is a specification.

This invention relates to automatic firearms in which the breech piece is not locked in its forward position but is released from its rear position and projected forwardly on actuating the trigger, the object of the invention being to overcome the drawbacks of the known automatic fire-arms of this type.

The aforesaid drawbacks consisted in that a considerable recoil was still perceptible and, where there was a strong powder charge, the cartridge case easily burst during the firing of the shot. These defects are due to the fact that the firing of the cartridges does not take place until the breech piece has reached the cartridge chamber. The explosive energy of the powder gases in such cases thus re-acts with its full force on the breech-piece and produces the objectionably heavy recoil. Moreover, if the cartridge case is withdrawn from the cartridge chamber immediately after igniting the charge, as is usually the case, the cartridge case is no longer inclosed and consequently tears. On account of these defects only small-caliber fire-arms have hitherto been constructed to load automatically.

According to the present invention, the cartridge chamber is provided with an extension adapted to receive a plunger on the end of the breech piece when the latter moves forward. The ignition is adapted to take place before the breech piece reaches its foremost position, that is to say, when it possesses its greatest kinetic energy, and before the cartridge inclosed in the cartridge chamber has attained its final position. The breech piece continues to move forwardly during the firing of the shot, by virtue of its kinetic energy, and thus insures an absolutely gas-tight closure of the rear end of the barrel and reduces the recoil, which is then only sufficient to return the breech piece to its rear position. The cartridge case is at the same time inclosed in the cartridge chamber so that the rearwardly-acting gas pressure cannot burst it. When the shot has left the barrel the gas pressure in the barrel is destroyed and the

cartridge case can then be withdrawn from the cartridge chamber without being damaged.

The ignition, as already stated, takes place before the breech piece has ended its forward movement, the ignition being effected by an unlocking-device acting on the firing-pin in the breech piece. This offers the advantage that the recoil acts on a member of considerable mass which is projected in the opposite direction to the recoil and which thus possesses considerable kinetic energy. The kinetic energy of this member must first of all be destroyed and thereby a considerable part of the recoil is consumed. The breech piece must moreover, be returned to its rear position and finally the spring which projects it has to be compressed before a new shot can be fired by the manipulation of the trigger. This destruction of the kinetic energy of a forwardly moving mass is a particular feature of the present invention and, in combination with the aforesaid advanced ignition and the extension of the cartridge chamber, enables automatic fire-arms of large caliber, thus having a greater powder charge, to be manufactured.

By employing a breech spring of the necessary strength and by the use of a sufficiently heavy breech piece, its kinetic energy may also be utilized to increase the velocity of the shot.

The invention is illustrated by way of example in the accompanying drawings in which—

Figure 1 is a longitudinal vertical sectional view showing the breech and firing mechanism of an automatic fire-arm, only such parts being illustrated as are necessary to clearly understand the present invention. Fig. 2 shows the same in horizontal section. Fig. 3 is an end view of the breech piece as seen from the left of Figs. 1 and 2. Fig. 4 is a view of the opposite end of the breech piece and Fig. 5 is a sectional view taken through the magazine.

The breech case *g* is closed at the rear by a screw-threaded cap *y* bearing against spring *f*.

In Figs. 1 and 2 the breech piece or bolt *a*, situated within the breech case is shown in the position it assumes after being drawn back by the handle *b* so that the pawl *c* engages behind the shoulder *x*. The pawl *c* is held in the position shown in Fig. 1 by a spring *w* and is released by the actuation of

the lever *v*. At the front end of the bolt *a* is a plunger *d* which is fitted at the front with a spring-catch *n* and terminates at the rear in a conical part *t* adjoining the bolt *a*. The conical part *t* is complementary to a hollow conical part *t*¹ in the end *g*¹ of the breech case *g* in which is screwed the barrel *l* which is provided with a cartridge chamber *m*. Inside the bolt *a* is a firing pin *k* which is prevented from automatically moving forward by a spring *u*. A hammer *h* engages behind the firing pin *k* and the rear end of the bolt *a* has a groove *s* in the same plane as a shoulder *h*¹, on the hammer *h*. In the same plane is also situated a pawl *i* which is secured to the breech case *g* by a spring *i*¹ and projects through an opening *i*² in the breech case. Laterally of the breech is mounted the magazine *z* containing the cartridges *p* with their cases *p*¹ each of which has a neck at its rear end terminating in a disk *e* of a smaller diameter than the cartridge case *p*¹. The small diameter of the disk *e* enables the catch *n* to engage the cartridge when the latter is situated in the cartridge chamber without necessitating the provision of a recess or other means in the cartridge chamber for the reception of the catch. Projecting into the breech is a cartridge ejector *o* (Figs. 1 and 5).

The operation of the aforesaid mechanism is as follows. When the lever *v* is actuated, the pawl *c* releases the bolt *a* which is projected forwardly by the spring *f* and strikes against the innermost cartridge *p*, pushing it into the cartridge chamber *m*, the hollow conical part *t*¹ guiding the cartridge and the disk *e* engaging behind the catch *n* on the plunger *d*. The plunger fits tightly in the cartridge chamber *m* as indicated in dotted lines in Fig. 1 and covers a considerable distance within the cartridge chamber *m* before the conical part *t* of the bolt can abut against the hollow conical part *t*¹ on the breech case. During the forward movement of the bolt *a*, and as soon as the groove *s* comes in front of the pawl *i*, the latter enters the groove *s* under the action of the spring *i*¹ and actuates the hammer *h* when the plunger *d* has entered the cartridge chamber *m* but before it has ended its forward movement. The firing pin *k* is thus driven forward against the action of the spring *u* and effects the ignition. At the moment of ignition the bolt *a* is still in forward movement but it now moves against the force of the powder gases and is thereby retarded, the pressure of the gases retarding the bolt *a* against the action of the spring *f* so that finally the pawl *c* automatically springs behind the shoulder *x*. It is thus only necessary to manipulate the handle *b* when putting the fire-arm in readiness for action.

The invention moreover enables the velocity of the shot to be increased although the bolt is not locked in its forward position, for which purpose the kinetic energy of the bolt, which is dependent on the weight of the bolt and on the bolt spring, should be so great that it overcomes the initial pressure of the powder gases, the bolt being first brought to a state of rest by the maximum gas pressure.

The length of the cartridge chamber *m* in the barrel *l* must be such that the projectile will leave the barrel *l* before the cartridge case *p*¹ is withdrawn out of the cartridge chamber *m* by the catch *n*. On its return the cartridge case runs against the ejector *o* and is ejected.

I claim:

1. In an automatic fire-arm the combination of a breech chamber, a cartridge chamber of greater length than the cartridge at the front end of said breech chamber, a breech piece movable in said breech chamber, a projection on the front end of said breech piece adapted to accurately fit into said cartridge chamber, means for projecting said breech piece toward the front, a firing pin carried by said breech piece and automatic means for insuring the actuation of said pin shortly before said breech piece completes its forward movement.

2. In an automatic fire-arm the combination of a breech chamber, a cartridge chamber of greater length than the cartridge at the front end of said breech chamber, a breech piece movable in said breech chamber, a projection on the front end of said breech piece adapted to accurately fit into said cartridge chamber, means for projecting said breech piece toward the front, a firing pin carried by said breech piece and automatic means for insuring the actuation of said pin shortly before said breech piece completes its forward movement, means for automatically locking said breech piece in its rear position, and mechanism for releasing said breech piece.

3. In an automatic fire-arm the combination of a breech chamber, a cartridge chamber of greater length than the cartridge at the front end of said breech chamber, said cartridge chamber terminating at its rear in a conical part, a breech piece movable in said breech chamber and having a conical shoulder and a reduced part in front of said shoulder adapted to accurately fit into said cartridge chamber, means for projecting said breech piece toward the front, a firing pin carried by said breech piece and automatic means for insuring the actuation of said pin shortly before said breech piece completes its forward movement.

4. In an automatic fire-arm the combination of a breech chamber, a cartridge chamber of greater length than the cartridge at

- the front of said breech chamber, a breech piece movable in said breech chamber, a projection on the front end of said breech piece adapted to accurately fit into said cartridge chamber, a spring for projecting said breech piece toward the front, a catch adapted to arrest said breech piece in its rear position, mechanism for releasing said catch, a firing-pin carried by said breech piece, a hammer on said breech piece adapted to strike said pin, and means for automatically actuating said hammer shortly before said breech piece completes its forward movement. 10
- 15 5. In an automatic fire-arm the combination of a breech chamber, a cartridge chamber of greater length than the cartridge at the front end of said breech chamber, a breech piece movable in said breech chamber, a projection on the front end of said breech piece adapted to accurately fit into said cartridge chamber, a spring for projecting said breech piece toward the front, a catch adapted to arrest said breech piece in its rear position, mechanism for releasing said catch, a firing-pin carried by said breech piece, a hammer on said breech piece adapted to strike said pin, and a detent secured to said breech chamber in such a 25 position as to actuate said hammer shortly before said breech piece completes its forward movement. 30
6. In an automatic fire arm, a breech chamber, a cartridge chamber, a movable breech piece adapted to move forward to press the cartridge into the cartridge chamber and automatic means for firing the cartridge shortly before it is pressed into final position, whereby the kinetic energy of the breech piece is such that, after being overcome by the powder gases, the pressure of the gases is just sufficient to return said breech piece. 40
7. In an automatic fire-arm, a breech chamber, a cartridge chamber, a movable breech piece adapted to move forward to press the cartridge into the cartridge chamber and automatic means for firing the cartridge shortly before it is pressed into final position, whereby the kinetic energy of the breech piece is such that the initial pressure of the powder gases is overcome by said breech piece and the latter only brought to rest by the maximum gas pressure. 50
- 55 8. In an automatic fire-arm the combination of a breech chamber, a cartridge chamber of greater length than the cartridge at the front end of said breech chamber, a breech piece movable in said breech chamber, a projection on the front end of said breech piece adapted to accurately fit into said cartridge chamber, means for projecting said breech piece toward the front, a firing pin carried by said breech piece and automatic means for insuring the actuation 60
- of said pin shortly before said breech piece completes its forward movement, and a spring catch on the end of said breech piece adapted to engage a reduced head on the cartridge and to fit between the head thereof and the cartridge chamber. 70
9. In an automatic fire-arm the combination of a breech chamber, a cartridge chamber of greater length than the cartridge at the front end of said breech chamber, said cartridge chamber terminating at its rear in a conical part, a breech piece movable in said breech chamber and having a conical shoulder and a reduced part in front of said shoulder adapted to accurately fit into said cartridge chamber, means for projecting said breech piece toward the front, a firing pin carried by said breech piece and automatic means for insuring the actuation of said pin shortly before said breech piece completes its forward movement, and a spring catch on the end of said breech piece adapted to engage a reduced head on the cartridge and to fit between the head thereof and the cartridge chamber. 80
10. In an automatic fire-arm the combination of a breech chamber, a cartridge chamber of greater length than the cartridge at the front end of said breech chamber, a breech piece movable in said breech chamber, a projection on the front end of said breech piece adapted to accurately fit into said cartridge chamber, a spring for projecting said breech piece toward the front, a catch adapted to arrest said breech piece in its rear position, mechanism for releasing said catch, a firing-pin carried by said breech-piece, a hammer on said breech piece adapted to strike said pin, and means for automatically actuating said hammer shortly before said breech piece completes its forward movement, and a spring catch on the end of said breech piece adapted to engage a reduced head on the cartridge and to fit between the head thereof and the cartridge chamber. 90
11. In an automatic fire arm, a breech chamber, a cartridge chamber, a movable breech piece adapted to move forward to press the cartridge into the cartridge chamber and automatic means for firing the cartridge shortly before it is pressed into final position, whereby the kinetic energy of the breech piece is such that, after being overcome by the powder gases, the pressure of the gases is just sufficient to return said breech piece, and a spring catch on the end of said breech piece adapted to engage a reduced head on the cartridge and to fit between the head thereof and the cartridge chamber. 100
12. In an automatic fire-arm, a breech chamber, a cartridge chamber, a movable breech piece adapted to move forward to press the cartridge into the cartridge chamber. 110
13. In an automatic fire-arm the combination of a breech chamber, a cartridge chamber of greater length than the cartridge at the front end of said breech chamber, a breech piece movable in said breech chamber, a projection on the front end of said breech piece adapted to accurately fit into said cartridge chamber, means for projecting said breech piece toward the front, a firing pin carried by said breech piece and automatic means for insuring the actuation 120
14. In an automatic fire-arm the combination of a breech chamber, a cartridge chamber of greater length than the cartridge at the front end of said breech chamber, a breech piece movable in said breech chamber, a projection on the front end of said breech piece adapted to accurately fit into said cartridge chamber, a spring for projecting said breech piece toward the front, a catch adapted to arrest said breech piece in its rear position, mechanism for releasing said catch, a firing-pin carried by said breech-piece, a hammer on said breech piece adapted to strike said pin, and means for automatically actuating said hammer shortly before said breech piece completes its forward movement, and a spring catch on the end of said breech piece adapted to engage a reduced head on the cartridge and to fit between the head thereof and the cartridge chamber. 125
15. In an automatic fire-arm the combination of a breech chamber, a cartridge chamber of greater length than the cartridge at the front end of said breech chamber, a breech piece movable in said breech chamber, a projection on the front end of said breech piece adapted to accurately fit into said cartridge chamber, a spring for projecting said breech piece toward the front, a catch adapted to arrest said breech piece in its rear position, mechanism for releasing said catch, a firing-pin carried by said breech-piece, a hammer on said breech piece adapted to strike said pin, and a detent secured to said breech chamber in such a position as to actuate said hammer shortly before said breech piece completes its forward movement. 130

ber and automatic means for firing the cartridge shortly before it is pressed into final position, whereby the kinetic energy of the breech piece is such that the initial pressure of the powder gases is overcome by said breech piece and the latter only brought to rest by the maximum gas pressure, and a spring catch on the end of said breech piece adapted to engage a reduced head on the

cartridge and to fit between the head thereof and the cartridge chamber.

In testimony whereof I affix my signature in presence of two witnesses.

REINHOLD BECKER.
